UNITED STATES PATENT OFFICE.

VINZENT RUDOLF ROSTEK, OF PHILADELPHIA, PENNSYLVANIA.

COOLER FOR STILLS.

Application filed November 14, 1928. Serial No. 319,227.

My invention relates to new and useful improvements in a cooler for stills and has for one of its objects to provide an exceedingly simple and effective device of this character 5 in which the heat transfer elements or the distributor and the chamber containing the distributor may be easily and quickly cleaned.

Another object of the invention is to provide the construction of the cooler in which 10 the distributor element may be readily disassembled and easily reassembled for cleaning and sterilizing.

A further object of the invention is to provide a cooler which will be simple in construction and one which will require but a small amount of metal to produce the distributor and the barrel forming the inner wall of the water jacket and which also provides the chamber for the distributor. 20 This is particularly advantageous where expensive metals are used for the formation of the above mentioned parts.

The cooler such as herein contemplated may be used for the distillation of water, alcohol, 25 oils and acids, and I have found that in the distillation of some of these, particularly certain of the acids, it is necessary to use very expensive metals for the parts through which the acid elements pass, such as gold and silver. By constructing the parts as herein shown, a very substantial saving in metal is accomplished thereby reducing the cost of manufacture. Further, by making the parts 30 removable, they may be disassembled and cleaned after each run and the parts easily cleaned to remove any residue or clean out oxidation which might be detrimental to the next substance to be distilled.

With the above in mind it is one of the objects to provide a chamber for the reception 40 of water in circulation, said chamber having a barrel passing therethrough to provide a condensing chamber, the latter having a removable vapor distributing means therein 45 exemplified by a perforated tube.

With these ends in view, this invention consists in the details of construction and combination of elements hereinafter set forth and then specifically designated by the claims.

50 In order that those skilled in the art to which this invention appertains may understand how to make and use the same, I will de-

scribe its construction in detail, referring by numerals to the accompanying drawings forming a part of this application, in which:

Fig. 1, is a longitudinal sectional view of a cooler constructed in accordance with my invention, some of the parts being left in elevation and showing its connection with a still and an outlet conduit.

Fig. 2, is a section at the line 2—2 of Fig. 1.

In carrying out my invention as herein embodied, 3 represents a still of any ordinary or desirable construction which is heated in the usual manner to change the liquid or fluid contents into a vapor, the latter being carried off through a suitable conduit or goose neck 4.

The outer end of the goose neck is detachably connected to one end of the cooler 5 by means of a suitable union nut 6 coacting with the flange 7 on the goose neck and having threaded connection as at 8 with one of the reduced ends of the barrel 9.

Both ends of said barrel are reduced in diameter relative to the intermediate or major portion thereof so that the ends of the tubular distributor 10 will snugly fit in said reduced ends of the barrel while the intermediate portion of said tube will be spaced from the intermediate portion of the barrel, thus providing a condensing chamber 11. The tube 10 is held in place at one end by the union nut 6 and at the other end by the cap 12 having threaded engagement with the outer end of the barrel 9 and said cap also acts as a closure for both the tube and barrel as will be readily understood.

The tube 10 is provided with any number of perforations 13, but these are preferably so arranged or located that they gradually increase in number toward the outer end of the tube and some of the ones nearer the outer end are at higher elevations than the other ones. This arrangement prevents the vapor leaving the tube all at one end, or in other words, the particular arrangement of the apertures causes the vapor to be distributed to the condensing chamber at different points. Of course the size of the apertures will also govern this to some extent as will be obvious.

The condensation accumulating in the condensing chamber 11 will flow off to a point of disposal through an outlet conduit 14 con-

nected at a suitable point in the lower portion of the barrel 9 and this outlet conduit is provided with a trap 15 to prevent escape of any vapor prior to condensation.

5 Surrounding the major intermediate portion of the barrel is a tank, receptacle or container forming a water cooling chamber 17 and the walls of this container have water tight joints with the barrel 9, outlet conduit 14 and any other pipes which may pass through or be connected therewith.

Water or any other cooling medium is circulated through the cooling chamber by means of an inlet pipe 18 provided with a perforated header 19 and an outlet pipe 20. The inlet pipe 18 leads to the header which is located adjacent the bottom of the cooling chamber so that the cooling medium will flow into the bottom of said cooling chamber and as it becomes heated it will rise to the top of said chamber and pass off through the outlet pipe 20.

From the foregoing description, it will be noted that when the contents of the still are vaporized, the vapor will then flow into the distributor 10 and pass therefrom at different points through the perforations 13 into the condensing chamber 11 being condensed by the low temperature of said chamber due to the flow of a cooling medium thereabout within the cooling chamber 17 and as the condensation takes place, the contents will flow off through the outlet pipe 14 to any suitable point of disposal.

35 After the distilling operations have been completed, either the union nut 6 or the cap 12 or both may be removed and the distributor disassembled so that the condensing chamber and the inner walls of the barrel 9 and the distributor both inside and outside may be readily cleaned.

It is to be particularly noted that the barrel 9 and the distributor may be relatively small in size and of short lengths so that they will be inexpensive as compared to the great amount of metal necessary in the formation of the usual coil and yet the same result will be accomplished since none of the vapor can escape until complete condensation has taken place.

There are two points to which I desire to call attention, the first and foremost one being the ease with which the parts of the cooler may be readily cleaned and the other is the small amount of metal necessary to produce the barrel and distributor.

Of course I do not wish to be limited to the exact details of construction as herein shown, as these may be varied within the limits of

the appended claims without departing from the spirit of my invention.

Having thus fully described my invention, what I claim as new and useful is:

1. A cooler for stills consisting of a container to provide a chamber for the circulation of a cooling medium, a barrel mounted within the container and having its ends projecting therefrom, a distributor removably mounted within said barrel, means to detachably connect the outlet of a still with one end of said distributor, and means for carrying off the condensate from the barrel.

2. A cooler for stills comprising a container, a barrel mounted within said container with its ends projecting outside thereof, said ends being of less diameter than the intermediate portion, means to provide a circulation of a cooling medium through the container, a perforated tubular distributor having its ends mounted in the reduced ends of the barrel whereby the intermediate perforated portion is spaced from the intermediate walls of the barrel to produce a condensing chamber, means for connecting one end of the distributor with the outlet of a still, said means also functioning as a closure for the contiguous end of the barrel, means acting as a closure for the opposite ends of the distributor and barrel, and a conduit connected with the barrel whereby the condensate may flow therefrom.

3. The structure set forth in claim 2 wherein the apertures in the distributor increase in number toward the outer end with some of the succeeding ones arranged at higher elevations than the preceding ones.

4. In a device of the kind described, a barrel open from end to end, a tubular perforated distributor also open from end to end and having its ends mounted in the ends of the barrel with the intermediate portions spaced from the intermediate portion of said barrel, means to close the outer ends of the barrel and distributor, means to close the inner end of the barrel and act as a connector for temporarily attaching the inner end of the distributor to the outlet of a still, an outlet conduit leading from the barrel, a container surrounding the intermediate portion of the barrel and forming therewith a cooling chamber, an inlet pipe leading to the bottom of the container, a header on the inner end of said inlet pipe and an outlet pipe leading from the top of the container.

In testimony whereof, I have hereunto affixed my signature.

VINZENT RUDOLF ROSTEK.
